 Boston, Mass., a corporation of Massachusetts

Application July 27, 1939, Serial No. 286,826

2 Claims. (Cl. 101—416)

My invention relates to apparatus for printing or coating a web and drying it.

The invention, which has among its objects the provision of improved apparatus of the character mentioned, including improved web drying means, will be best understood from the following description and accompanying drawings, while the scope of the invention will be more particularly pointed out in the appended claims.

In the drawings:

Figs. 1 and 2 together constitute a side elevation of the printing press according to the invention, Fig. 1 showing one end of the machine, and Fig. 2 the opposite end;

Fig. 3 is a longitudinal vertical section of the drying mechanism according to Fig. 1 on an enlarged scale, with parts in elevation and parts omitted;

Figs. 4, 5 and 6 are, respectively, sections on the lines 4—4, 5—5 and 6—6 of Fig. 3, the section line 6—6 for convenience in following the drawings also being placed on Fig. 10;

Fig. 7 is a section on the line 7—7 of Fig. 8, with parts omitted;

Figs. 8 and 9 are, respectively, sections on the lines 8—8 and 9—9 of Fig. 3 on an enlarged scale, with parts omitted;

Fig. 10 is a section on the line 10—10 of Fig. 9;

Fig. 11 is an elevation of one side of the drier lifting mechanism, corresponding to a section on the line 11—11 of Fig. 2, with parts omitted;

Fig. 12 is a section on the line 12—12 of Fig. 11;

Fig. 13 is a plan of the mechanism according to Figs. 11 and 12;

Fig. 14 is a section on the line 14—14 of Fig. 12;

Fig. 15 illustrates a detail of the mechanism according to Figs. 11 to 14; and

Fig. 16 is a section on the line 16—16 of Fig. 15.

Referring to the drawings, the apparatus illustrated is a multi-color press, each printing couple for example being constructed as illustrated in applicant's co-pending application Serial No. 209,284, filed May 21, 1938.

In the apparatus illustrated a length of web W is fed from a roll of web 1 through a plurality of printing couples each comprising the print roll or cylinder 3 and impression roll or cylinder 5. All or any of these couples however may act to coat the web instead of print upon it, or, for example, could be the squeeze rolls for removing excess coating or impregnating liquid from the web after it is immersed in such liquid.

The web after passing through the series of roll couples 3 and 5 passes to the rewind reel 7. As illustrated, the web after leaving each

couple passes through a drier, the several driers being supported by bars 9 (Figs. 1 and 5) carried by posts 11 extending upwardly from the side standards 13 which support the rolls 3 and 5 of the printing couples.

Referring particularly to Figs. 3, 6, 9 and 10, the web after leaving the first and second roll couples 3, 5 is guided by suitable rolls 15 into the casing 17 of a drier, passing into that casing through a slot 19 (Fig. 3) formed in the end wall 21 thereof. Similarly suitable rolls 23 and 25 guide the web from the casing through a slot 27 in the opposite casing end wall 29. The web is then guided to the next roll couple 3, 5 by suitable rolls 31 carried by the standards 13 which support that couple, and after passing through the latter couple passes into and through the next successive drier. Each of those driers which respectively are between the first and second, and second and third, couples 3, 5 are alike, and therefore only one need be described.

The casing of each of the driers just mentioned besides the end walls 21 and 29 comprises the top wall 33, bottom wall 35, and opposite side walls 37 and 39, the latter through the greater part of its extent having an opening closed by the normally shut door 41, which opening provides access to the interior of the casing. As shown, the door may be supported by hinges 43 and detachably secured in closed position by latches 45 (Figs. 1 and 6). Otherwise the casing is preferably substantially permanently closed except for the slots 19 and the air inlet opening 47 and air exit opening 49.

Interiorly of the casing described in the preceding paragraph is an air distributing conduit. This conduit, as best shown in Fig. 6, is of rectangular cross-section, and has an intermediate portion 51 (Fig. 10) the bottom wall 53 of which rests upon the bottom wall 35 of the casing which contains it, and further has upwardly inclined end portions 55. The upper wall 57 of the conduit in this way is so formed as to be in parallel relation to the path of the web as determined by the rolls 15, 23 and 25, as will be clear from Fig. 3. In the bottom wall 53 of the conduit is shown an opening 59 (Figs. 6 and 10) communicating with the air inlet opening 47 in the bottom wall 35 of the casing which receives the conduit. In this way atmospheric air may be forced into the conduit by the blower 61 driven by the electric motor 63, the motor and blower unit being carried by the bottom wall 35 of the casing.

The upper wall 59 of the air distributing conduit 51, 55, as shown, is provided with spaced

transversely extending slots 65 running substantially across its width for directing air against the web for drying the latter. If desired, this air may be heated. As illustrated, for that purpose a series of parallel bar-like resistance elements 67 (Figs. 6, 9 and 10) extending transversely of the conduit may be provided, these resistance elements being shown in the drawings more or less diagrammatically and being supported in any convenient way in insulated relation to the casing and energized by suitable leads (not shown). As illustrated, the bars are placed above the opening 59, and above the bars is placed an open ended channel-shaped baffle 69 extending transversely of the conduit. In this way the incoming air is forced to flow in opposite directions through the channel 69 in contact with the bars, which facilitates heating of the air.

As illustrated in Figs. 9 and 10, these slots 65 which are adjacent the end of the casing opposite the air exit opening 49 may be provided with baffles 71 for directing the air discharged from the slots away from the slot 19 through which the web enters the casing. The slots 65 at the opposite end of the casing adjacent the web exit slot 27 also, if desired, may be provided with the baffles 71 for directing the air away from the slot 27. Ordinarily as these latter slots 65 are adjacent the air exit opening 49, which, as herein-after explained, is subjected to suction, the baffles 71 at that end of the conduit will be unnecessary.

It will be understood that when the rolls 3 of the couples 3, 5 are substituted by larger rolls 3, 35 as might be necessary from time to time in a printing press, it will be necessary to adjust the position of the drier receiving the web leaving such couple. For this purpose in the present embodiment of the invention the casing for each drier is supported by a frame comprising the bars 13 at opposite sides of the upper portion thereof. These bars, as shown, are pivotally supported at 75 on brackets 11 rigidly carried by the bars 9. At its opposite end the drier is adjustably supported by mechanism which will now be described.

As illustrated, the roll 15 at the entrance side of the slot 19 (Fig. 3) is rotatably supported on a stationary arbor 16 (Figs. 3 and 11). This arbor is conveniently carried at opposite ends by the bars 13, the rolls, as will be understood by those skilled in the art, being held against longitudinal movement on the arbor by suitable collars 79 (Fig. 11). The arbor at each end thereof extends beyond the adjacent bar 13, as shown in Figs. 11 and 12, and rotatably supports a block 81, to which latter is rigidly attached the lower end of a rack bar 83, the upper end of each rack bar being adjustably connected to the bar 9 at the same side of the machine by the mechanism best illustrated in Figs. 11 to 15.

As shown, each bar 9 at its inner side has secured thereto a lug 85 (Figs. 3 and 11) which carries a bearing 87. Rotatably mounted in these bearings is a shaft 89 carrying at one end a handwheel 91 (Figs. 1 and 11), whereby the shaft may be rotated. As illustrated, the hub 93 of the handwheel is fixed to the shaft 89 by a suitable pin 95, and rotatably mounted on the shaft between that hub and the adjacent bearing 87 is the hub 97 of a ratchet wheel 99 and a block comprising the body portion 101 and cover 103, the cover being attached to the block by use of suitable screws 105 (Figs. 11, 15 and 16). 75

There may be a handwheel at each end of the shaft so that the drier may be adjusted from either side of the machine, but ordinarily it will be satisfactory if but one handwheel is employed for that purpose, and in such case at the opposite end of the shaft from that shown in Fig. 11 a collar corresponding to the hub 93 of the handwheel may be pinned to the shaft.

For rotatably mounting the blocks 101, 103 on 10 the shaft 89 each block is provided with spaced ears 107 having perforations 109 through which the shaft 89 passes. As shown, each block is provided with an opening 111 of rectangular cross-section which receives and guides the adjacent rack bar 83. Meshing with each rack bar is a rack pinion 113 keyed at 115 (Fig. 14) to the shaft 89, the body portions 101 of the blocks being cut away to form openings 117 permitting the rack pinions to mesh with the racks. In this way when the shaft 89 is rotated the rack pinions will raise or lower the rack bars to swing the driers about the pivotal supports 75.

The hubs 97 of the ratchet wheels 99 are keyed to the shafts 89 as shown at 119 (Figs. 12 and 14). Cooperating with the teeth 121 of the ratchet wheels are pawls 123 pivotally supported at 125 to projections 127 on the cover members 103 of the blocks 101, 103. At their upper sides these projections carry leaf springs 129 for resiliently pressing the pawls into operative relation with the rack teeth. There need be but one pawl and ratchet wheel for each shaft, but conveniently one is located adjacent each rack bar 83, the two being identical and fixed to the shaft in such relation that the teeth of one are angularly spaced from the other one-half the pitch of the ratchet teeth so as to enable a finer adjustment of the drier to be secured.

In the machine illustrated the web W after 40 passing through the couple 3, 5 at the left hand side of Fig. 1 passes into a drier at the upper side of the bars 9, the web being so guided by the rolls 131 and 133 and the drier rolls 135 that the same side of the web is treated with air as in the preceding driers.

The drier at the upper side of the bars 9 is best illustrated in Figs. 1, 3, 5, 7 and 8. It comprises a casing 137 of the same general shape and construction as that heretofore described, the end walls of the casing, as will be clear from Fig. 3, having a web entrance opening 139 and a web exit opening 141.

At its upper side the casing 137 has, adjacent one end thereof, an air inlet opening 143 (Fig. 3) through which air is forced into a distributing conduit 144 by a blower 145 driven by an electric motor 147. At its upper side adjacent its opposite end it has an air exit opening 149. In its bottom it has openings 151 communicating with the air exit openings 49 of the casings of the lower driers, such communication being established by flexible conduits 153 which permit adjustment of the lower driers. To the air exit opening 149 of the casing 137 is connected a conduit 155 through which air is withdrawn from the casing by an exhauster 157 driven by an electric motor 159 for discharging the air and fumes withdrawn to any convenient place of disposal.

The air distributing conduit 144 in the upper drier is best illustrated in Figs. 4, 5, 7 and 8. This conduit has a bottom wall 161 of such shape as to be parallel with the web. Extending transversely across this wall are spaced air exit slots 163 formed in the wall for directing air against the web. In its upper wall 165 the

conduit also has an opening 167 communicating with the casing air inlet opening 143. Beneath this opening are parallel electric resistance elements 169 similar to the electric resistance elements 67 of the other driers, these elements being covered by the channel-shaped baffle 171 (Figs. 3 and 4) similar to the channel-shaped baffle 69 of the other driers.

It will be observed that in all of the foregoing drier constructions air is forced into a distributing conduit from which the air is discharged against a web passing through a casing, the latter having openings through which the web enters and leaves it. Such constructions, unless means are provided to prevent it, will permit the air to discharge into the room containing the apparatus, which would be highly objectionable under most conditions in that it would fill the room with fumes from the ink or coating material being dried. To prevent this the exhauster 157 is of such capacity as to withdraw from each casing at the discharge side of the air distributing conduit therein the air and fumes at such rate as will maintain a pressure in the casings not greater than atmospheric, and preferably just below atmospheric, so as to prevent discharge of air and fumes through the web entrance and exit slots and other openings which may exist in the drier casings.

It will be understood that, within the scope of the appended claims, wide deviations may be made from the forms of the invention herein described without departing from the spirit of the invention.

I claim:

1. A printing press having, in combination, spaced printing couples each comprising cooper-

ating printing and impression cylinders, means for passing a web through said couples in series comprising a drier for the web, said drier comprising an elongated casing positioned between said couples in an inclined position, said casing carrying web guide means movable therewith and comprising at one end portion thereof a wall having a slot for the passage of the web, which slot is positioned adjacent one of said couples in parallel relation to the axes of the cylinders of such couple adjacent a horizontal plane which includes their line of tangency, said drier adjacent the opposite end portion of the casing being supported adjacent the other couple for swinging about an axis above the line of tangency of the cylinders thereof parallel to the axes of said cylinders, and means for moving said drier for raising and lowering the first mentioned end portion of said casing for adjusting said slot into operative relation with printing cylinders of different diameters.

2. In a printing press, a pair of spaced printing couples each comprising a cooperating horizontal printing cylinder and impression cylinder, a casing providing an elongated drying chamber for the web which passes through said couples in series positioned in inclined position between said couples with opposite ends adjacent said couples, respectively, said casing carrying web guide means movable therewith, means supporting said casing adjacent the higher end thereof for swinging about a horizontal axis, and means for raising and lowering the opposite lower end of said casing into operative relation with printing cylinders of different diameters.

LEROY Q. PRESBY.
